UNITED STATES PATENT OFFICE.

THOMAS J. MULLEN AND THOMAS F. BRENNAN, OF NEW BRIGHTON, NEW YORK.

SAND-BOX.

No. 926,586.

Specification of Letters Patent.

Patented June 29, 1909.

Application filed January 8, 1909. Serial No. 471,327.

To all whom it may concern:

Be it known that we, THOMAS J. MULLEN and THOMAS F. BRENNAN, citizens of the United States, residing at New Brighton, in the county of Richmond and State of New York, have invented certain new and useful Improvements in Sand-Boxes; and we do hereby declare the following to be a full, clear, and exact description of the invention, such as will enable others skilled in the art to which it appertains to make and use the same.

This invention relates to sand boxes, and especially to sand boxes employed for sanding rails of street railways and the like, and attached to street cars or similar vehicles.

An object of the present invention is to construct a sand box of improved form embodying improved features of convenience, strength, reliability and positive action.

A further object of the invention is to provide a sand box rigidly connected with the vehicle and having a sliding or swinging gate member connected with the flexible tubing adapted to conduct the sand discharged from the box to the rail.

A further object of the invention is to provide in combination with a stationary sand box a sliding or swinging gate member carrying an agitator disposed within the box adapted to agitate the sand to insure proper discharge.

A further object of the invention is to provide in combination with a stationary sand box and a movable gate member of an improved connection between such sand box and gate member.

With these and other objects in view the invention comprises certain novel constructions, combinations and arrangements of parts as will be hereinafter fully described and claimed.

In the drawings:—Figure 1 is a view of the improved sand box in vertical longitudinal section. Fig. 2 is a view of the sand box in side elevation. Fig. 3 is a view of the sand box in end elevation as indicated by arrow 3 of Figs. 1 and 2. Fig. 4 is a view of the sand box in side elevation with the links disposed in a slightly different relation to the box and gate. Fig. 5 is a view of the sand box in end elevation showing the resilient member as on arrow 5 of Fig. 4.

Like characters of reference designate corresponding parts throughout the several views.

The improved sand box forming the subject-matter of this application comprises substantially a hopper-shaped receptacle 10 of any approved or desired structure having its lower sides converging as at 11 producing an opening 12 in the underside of such receptacle.

Beneath the receptacle 10 a closure or opening 12 and slide 13 is disposed having formed along its sides parallel ribs 14 which prevent lateral movement of the slide relative to the hopper.

The hopper 10 is provided at the ends with ears 15 and upon the sides with studs or spindles 16 which may be formed integral therewith or may be as rivets with the inner ends upset or as bolts with the inner ends secured by nuts or in any of the usual and well known manners.

Upon the ears 15 links 17 are pivoted extending downwardly and also pivoted at their opposite ends to ears 18 in any approved manner as by bolts 19, similar pins or bolts 20 being employed to pivot the links 80 to the ears 15 and any ordinary and conventional means as the cotter-pins 21 being employed upon both pins to maintain such pins in position.

The sliding plate or gate 13 is provided with an opening 22 adapted at times to register with the opening 12 and to permit the discharge of sand from the hopper 10 through such opening 22 and an agitator 23 is carried rigidly by the plate extending upwardly within the hopper adapted to agitate the material therein to insure proper and reliable discharge from the opening 12 through the opening 22. The opening 22 is continued by a nipple upon which is secured 95 a flexible hose or coupling 24 of the usual and ordinary type employed for such purpose.

To maintain the gate or plate 13 in normal or closed position a spring 25 is rigidly secured to the hopper member in any approved place and by any approved means as to the flange 26 by means of the bolt 27 and is curved downwardly and provided with a slot 28 through which extends a threaded-bolt 29 having a hook 30 at one end engaging through a requisite opening in the plate 13 and with a tension nut 31 adapted to vary the tension of the spring 25 on the plate 13.

To operate the plate and to move it in the direction indicated by the arrow in Fig. 1 to open position any approved and ordinary

means may be employed here shown as the lever 32 which would extend upwardly into position for engagement by the motorman or other operator and connected in any approved manner as by a link 33 with the plate 13.

Instead of pivoting the links 17 to the ears 15 the links as 17' are in some instances pivotally mounted upon the studs 16. The 10 plate 13 is in such instance also provided with studs 34 forming a pivotal bearing for the lower ends of such links 17' and such links are held in position by cotter-pins 21 or in any approved manner.

15 It will be apparent that with the parts disposed as shown in Fig. 1, the escape of sand through the bottom opening 12 of the hopper is interrupted by the position of the gate 13 which is held to such position by the tension 20 of the spring 25. When, however, it is desirable to discharge sand from the hopper the lever 30 or equivalent means is manipulated moving the plate 13 in the direction indicated by the arrow thereby moving the 25 agitator 23 in the hopper to loosen the sand contained therein and also simultaneously moving the nipple 22 to register with the opening 12 whereby sand, by its own gravity, forced through such nipple and through 30 the pipe 24 is discharged as in the usual and ordinary manner. The release of the lever or equivalent means permits the spring 25 to close the plate 13 to the position shown at Fig. 1, whereby the flow is again interrupted.

35 What we claim is:—

1. In a device of the class described, a hopper, a plate movable relative to the

40 hopper, links pivoted to the hopper and to the plate, and means to move the plate upon the pivoted links.

2. In a device of the class described, a hopper provided with extending pivot members, a plate movable relative to the hopper and adapted to at times permit the discharge of material from the hopper, links pivoted to 45 the outstanding pivot means and to the plate, and means to move the plate.

3. In a device of the class described, a hopper, a plate movable relative to the hopper, links pivoted to the hopper, and to 50 the plate, a spring secured to the hopper, adjustable means connecting the spring with the plate, and means to move the plate against the tension of the spring.

4. In a device of the class described, a 55 receptacle provided with a discharge opening, a plate provided with a discharge opening movable relative to the receptacle and adapted at times to have its opening register with the opening of the receptacle, parallel 60 links pivoted upon the receptacle and also pivoted to the plate, means to normally hold the plate yieldingly out of register, and means to move the plate upon the pivots of the links to produce registration of the 65 openings.

In testimony whereof we affix our signatures in presence of two witnesses.

THOMAS J. MULLEN.
THOMAS F. BRENNAN.
